FLOOR SCRUBBING APPARATUS

Walter S. Finnell, Elkhart, Ind., assignor to
Finnell Systems, Inc., Elkhart, Ind., a corpora-
tion of Indiana

Application June 3, 1938, Serial No. 211,633

2 Claims. (Cl. 15—180)

This invention relates to floor scrubbing apparatuses.

The main objects of this invention are to provide improved means for thoroughly mixing the water and cleaning compound and spreading the same before it comes in contact with the scrubbing brushes proper; to provide a preliminary mixing and spreading of the water and cleaning compound such that when acted on by the rotating scrub brushes, a floor is thoroughly scrubbed and cleaned without streaks by one passage of the scrubbing machine over the floor; to provide an improved brush carrier of relatively large size but of light weight; to provide improved means for yieldingly mounting a brush holder to the carrier; to provide a brush holder mounting which is simple and durable in construction; to provide a yielding brush holder mounting which permits instant movement of the brush into depressions of the floor being scrubbed without frictional retardation; to provide an improved brush holder of simple and economical construction; and to provide a brush holder which will rigidly and securely retain the brush therein while permitting quick and ready removal therefrom and replacement thereof without the use of tools.

An illustrative embodiment of this invention is shown in the accompanying drawing, in which:

Fig. 1 is a top plan view of the brush carrier showing the position of the two annular series of brushes in dotted outline;

Fig. 2 is a view in side elevation of a brush and brush holder secured to the under side of the carrier plate when the carrier is raised from the floor;

Fig. 3 is an enlarged, fragmentary sectional view taken on the line 3—3 of Fig. 1;

Fig. 4 is an enlarged top plan view of a brush holder with a brush secured therein; and

Fig. 5 is an enlarged, fragmentary sectional view taken on the line 5—5 of Fig. 1, showing a brush and brush holder secured to the carrier with the brush resting on the floor and sufficient pressure on the brush carrier to bring the brush into substantially parallel relation to the carrier.

In the use of a rotating brush carrier in scrubbing machines of the power driven type, it has been customary to introduce the water and cleaning compound into the middle of the carrier through the openings of a spider provided therein. Where the brush carrier is of relatively small dimensions so that the annular series of brushes, when viewed in plan, occupy a space of fifteen to eighteen inches, the action of the closely positioned brushes on the soap and water will thor-

oughly mix the same and at the same time effect a thorough scrubbing of the floor without streaking.

It has been found, however, that in the use of a scrub brush carrier of this type of larger size, such as twenty inches and up in diameter, the brushes are located so far away from the middle of the brush holder that the water and cleaning compound is not properly mixed and spread so as to effect a thorough cleaning and scrubbing of the floor without streaking, particularly if it is desired to effect a thorough scrubbing of the floor in one passage of the machine over the floor surface.

In the present invention means have been provided for effecting a preliminary mixing of the water and cleaning compound and a spreading of the mixed material before it comes in contact with the main series of scrub brushes which are arranged adjacent the periphery of the disk-like brush carrier. By reason of this preliminary mixing and spreading of the water and cleaning compound, it has been found possible to secure a thorough and satisfactory scrubbing of the floor surface with one passage of the machine thereover without leaving any streaks.

In the construction shown in the drawing, a disk-like brush carrier 10, preferably of light weight material such as sheet metal, is provided with an axially positioned opening 11 therethrough in which is secured a spider 12 by means of bolts 13. The spider 12 is of relatively heavy weight and provides rigidity to the carrier 10 by being secured thereto at a plurality of points, the peripheral edge of the spider being provided with a ring-like rim 14 through which the bolts 13 extend.

The under side of the carrier 10 has an annular series of scrub brushes, generally designated 15 in Fig. 1, which are arranged concentrically with respect to the spider 12 and closely adjacent thereto, for the purpose of mixing and spreading water and cleaning compound which is passed through the openings 11 and spider 12 when the unit is being rotated on a floor during use. It will be understood that the scrubbing device, while being rotated, is also moved bodily along the floor by the machine to which it is attached and as this translation is accomplished, the mixed and spread water and cleaning compound is engaged and picked up by a second annular series of scrubbing brushes, which are the scrubbers proper and generally designated 16 in Fig. 1. The series of brushes 16 are arranged closely adjacent the peripheral edge of the carrier disk 10.

and effect a thorough and satisfactory scrubbing of the surface due to the preliminary mixing and spreading of the water and cleaning compound by the inner series of brushes 15.

The scrub brush units 15 and 16 are all of the same general construction and type and comprise a brush holder 17 in the form of a relatively broad channel having a web 18 which is adapted to receive the top side of a brush back 19 flush thereagainst. The brush holder is provided with flanges at the opposite edge thereof, the outer one 20 of which is generally arcuate shape when viewed in plan, and the lower edge of the flange is provided with a plurality of integrally formed prongs 21 which are bent inwardly, as shown most clearly in Fig. 4, so as to engage and bite into the outer side edge of the brush back 19, which edge is also of generally arcuate form to fit the holder.

The opposite flange 22 of the brush holder is relatively straight, except at its mid point where it is provided with an outwardly bulging pocket 23 which is adapted to receive and have seated therein a similarly shaped middle portion of a bowed leaf spring 24. The pocket 23 of the flange 22 and the spring 24 are provided with registering apertures therethrough for receiving a bolt 25 which secures and retains the spring 24 in its seat or pocket. The oppositely extending free ends of the spring 24 are provided with inwardly extending sharp prongs 26 which engage and bite into the opposite side edge of the brush back 19. The web 18 of the brush holder is also provided with a downwardly turned finger 27 at one end thereof which engages one end edge of the brush back 19 and forms a stop for preventing the brush from slipping rearwardly in the holder when the holder is moved in a direction opposite to the stop.

Each of the brush holders 17 is secured to the under side of the carrier 10 by means of a flat strap-like spring 28 which is formed in substantially U-shape but with the legs thereof diverging slightly outwardly when in normal uncomressed condition. The outer side of one leg of the spring 28 is secured against the under side of the carrier 10 by bolts 29 and the outer side of the other leg of the spring 28 is secured against the top surface of the web 18 of the brush holder 17 by bolts 30. The leg of the spring 28, which is secured to the brush holder, is longer than the leg which is secured to the carrier 10 and the extremity thereof is turned up at right angles to the leg to form a limit stop 31 which contacts the under surface of the carrier 10 when the brush is placed on the floor and pressure exerted downwardly on the carrier 10, as shown most clearly in Fig. 5 where the stop 31 is in contact with the under surface of the carrier 10.

In the operation of this improved scrubbing unit, carrier 10 is attached to a scrubbing machine in the usual manner for rotation and translatory movement over the floor to be scrubbed. Water and cleaning compound are fed into the middle of the carrier 10 through the opening 11 therein around the spider 12 and are spread and distributed by the inner series of mixing and spreading brushes 15. These

brushes, being located closely adjacent to the opening through the carrier, will pick up the cleaning compound and water, thoroughly mix the same, and spread it out, so that as the unit 5 is moved along the floor the outer series 16 of scrubbing brushes proper will be able to utilize the same and effect a thorough and satisfactory job of floor scrubbing without leaving objectionable streaks thereon. It will be understood, of course, that this unit is particularly adaptable for use in a floor scrubbing machine which removes the water from the floor immediately after the scrubbing is accomplished.

The brush holders 17, being mounted on the 15 U-shaped springs 28, will instantly move downwardly upon passing over any depression in the floor so that the scrub brush carried thereby will follow uneven contours in the floor surface. It is to be particularly noted that this mounting is free of frictional retardation and permits instant movement of the brush downwardly.

The scrub brushes may be readily installed and removed from the brush holder 17 by grasping the brush and moving it toward the bowed spring 24 until the prongs or teeth 21 formed on the 25 opposite flange are disengaged from the side edge of the brush back, at which time the brush is rotated downwardly clear of the flange 20 and prongs 21 and then moved away from the bowed spring 24. New brushes may be quickly installed by the reverse of the foregoing operation. In 30 this manner brushes may be installed, removed, or replaced quickly without the use of any tools and yet will be rigidly and securely retained in their holders.

Although but one specific embodiment of this invention has been herein shown and described, it will be understood that numerous details of the construction shown may be altered or 40 omitted without departing from the spirit of this invention as defined by the following claims.

What is claimed is:

1. A floor scrubber comprising a disk shaped brush carrier adapted to be rotated, said carrier having an opening therethrough adjacent its axis of rotation through which water and cleaning compound may be introduced, an annular series of unit brushes yieldingly secured to said carrier closely adjacent the opening therethrough for mixing and spreading such water and cleaning compound, and a second annular series of unit brushes yieldingly secured to said carrier in outward radially spaced relation to said first mentioned series for receiving the mixed and spread water and cleaning compound when said carrier is rotated on the floor.

2. A floor scrubber comprising a scrub brush carrying member, a scrub brush holder, and a flat strap-like spring formed in substantially U-shape, with the legs thereof normally diverging 45 outwardly, a side of one leg being secured to said brush carrying member in parallel relation thereto and a side of the other leg being secured to said brush holder, the end of one of said legs being bent toward the other at substantially right angles to provide a stop for limiting the movement of said legs toward each other.
